(57) **CLAIM**

The ornamental design for an exercise resistance band with handle, as shown and described.

DESCRIPTION

FIG. 1 is a perspective view of an exercise resistance band with handle showing another embodiment of our new design.

FIG. 2 is a cross-sectional view thereof, viewed along Section 11-11 of FIG. 1.

FIG. 3 is a front elevational view thereof; the opposing view is identical thereto.

FIG. 4 is a top plan view thereof.

FIG. 5 is a bottom plan view thereof.

FIG. 6 is an enlarged perspective view of a portion thereof.

(Continued)

FIG. 7 is a front elevational view of the portion of FIG. 6; the rear elevational view is identical thereto; and, FIG. 8 is a side elevational view of the portion of FIG. 6; the opposing side view is identical thereto. The broken lines in the figures form no part of the claimed design.
